ATTORNEY.

UNITED STATES PATENT OFFICE.

PETER K. HIGGINS, OF WACO, TEXAS, ASSIGNOR TO FREDERICK R. PARKER, OF CHICAGO, ILLINOIS.

ELECTRIC-LINE-APPARATUS PROTECTOR.

1,192,835.

Specification of Letters Patent. Patented July 25, 1916.

Original application filed October 22, 1903, Serial No. 178,140. Renewed July 22, 1913, Serial No. 780,371. Divided and this application filed December 15, 1913. Serial No. 806,826.

To all whom it may concern:

Be it known that I, PETER K. HIGGINS, a citizen of the United States of America, residing at Waco, in the county of McLennan and State of Texas, have invented a new and useful Electric-Line-Apparatus Protector, of which the following is a specification, reference being had to the accompanying drawings, illustrating same.

10 This application is a division of my co-pending United States patent application Serial No. 780,571, filed July 22, 1913, on electric line apparatus protectors, which is a renewal of application Serial No. 178,140 15 on the same invention.

My invention relates to means for protecting telephone and other electrical circuits and apparatus from damage from electricity which would be injurious to the circuits or apparatus connected therewith, and sometimes to the users of such apparatus; and the principal object thereof is to provide a simple and efficient device for that purpose.

25 Other objects will be apparent from the following specification.

I accomplish the desired results of this invention by means of the protector described herein, or modified forms thereof, the preferred form of which is illustrated in 30 the accompanying drawings in which—

Figure 1 is an end elevation of one form of the protector of the invention, and Fig. 2 is a longitudinal cross-section thereof with 35 portions shown in elevation.

Like characters refer to like parts in the several figures.

In the drawings, 1 is an insulating base for the protector, to which are suitably mounted metallic springs 2 and 3 which are adapted to normally stand in the positions 4 and 5, respectively, shown in dotted lines. To the lower ends of the springs 2 and 3 are connected the line conductors 6 and 7, respectively. The upper ends of the springs 2 and 3 are adapted to receive and hold the grooved metallic end terminals 8 and 9 of the body portion of the protector, preferably as shown. The metallic end terminals 8 and 9 are preferably provided with metallic studs 10 and 10 which project into sockets 11 and 11 in the resistance or graphite core 12, being preferably held in these sockets by a low-melting-point solder,

which is fused around the studs 10 and then allowed to cool, so as to unite the metallic end terminals 8 and 9 with the core 12. The core 12 is preferably a round rod and may be termed the thermal rod. The core 12 is preferably surrounded by a dielectric member 14, of celluloid or other suitable material, which may be perforated to provide an air space or multiple spark gap between the core 12 and the tube 13 of conducting material, preferably carbon, which surrounds the core 12. The tube 13 is preferably insulated from the metallic end terminals 8 and 9 by means of washers 15 and 16 of some suitable insulating material, preferably mica. It will be seen that the tube 13 is of noninflammable material and that it consequently protects the inflammable dielectric member or insulating material 14 from burning, under various conditions.

Secured to the base 1 may be a contact spring 17 the free end of which may engage the tube 13 when the body of the protector is in place between the springs 2 and 3 as shown in Fig. 2. This spring 17 is preferably connected by a conductor 18 with ground 19 or other suitable capacity. Secured to the base 1 and out of contact with spring 2 but adapted to be engaged thereby, may be a contact-member 20 which is preferably connected by conductor 21 to ground 19 or other suitable capacity.

After the body of the protector is assembled as shown, the free ends of springs 2 and 3 are pressed toward each other and engaged with the grooved end terminals 8 and 9 of the body of the protector, in a manner well understood, thereby holding the body portion of the protector securely in place between springs 2 and 3 and completing the main circuit through the protector from conductor 6 through spring 2, terminal 8, core 12, terminal 9, and spring 3 to conductor 7. Now, should a telephone or other line equipped with my protector become accidentally engaged with another line carrying a current of considerable volume but of low voltage, the resistance encountered in the graphite core 12 by the abnormal current traversing same would generate sufficient heat to soften or melt the solder which holds the studs 10 and 10 into the sockets 11 and 11, whereupon the springs 2 and 3 would cause

at least one of the metallic end terminals 8 and 9 to separate from the body of the protector, thus opening the main circuit there-through and permitting the spring 2 to engage the grounded contact 20 so as to switch the objectionable current off to ground. In this manner the objectionable current is prevented from injuriously affecting the apparatus connected with the conductor 7.

With the complete device as shown, should the telephone or other line become accidentally engaged with another line carrying a current of high voltage, this current would arc across the dielectric member 14 from the core 12 to the tube 13 and pass off to ground through the conducting tube 13, the contact spring 17 and conductor 18, thus being diverted from the apparatus to be protected. Lightning also will pass off to ground in the same manner. In case the arc continues, the dielectric 14 may become softened by the heat thereof, whereupon the spring 17 may press the conducting tube 13 into contact with the core 12 and thus break the arc, the current still passing off to ground through the spring 17 and conductor 18 as above stated.

After one or both of the end terminals 8 and 9 have separated from the body portion of the protector as above set forth, the protector may be repaired for further service by simply resoldering the terminals 8 and 9 to the body of the protector as originally, in any suitable manner.

The protector of this invention may be utilized in various places in electrical systems, as, for example, at the terminals of cables or lines entering central offices of telephone systems, and also at the subscribers' stations in such systems.

The features of the lightning arrester of this invention, and of the improved dielectric used therein, are described and claimed in the parent application above mentioned, of which this present application is a division.

I do not wish to limit this invention to all of the particular details herein set forth, as various modifications thereof may be made or utilized without departing from the scope of the appended claims. Neither do I wish to limit the materials of the device to those particularly specified, as other materials may also be used without departing from the scope and meaning of the appended claims.

What I claim as my invention is:

1. A protector for electrical circuits, comprising a resistance core, metallic ends secured to the said core by fusible substance, springs connected with the said metallic ends and having tension therein tending to pull the metallic ends away from the core, a dielectric substance around the said core, a tube of conducting material surrounding

the said dielectric substance, an insulating substance between the ends of the said tube and the said metallic ends, and means for connecting the said tube to ground.

2. A heat-cartridge having a carbonaceous resistance heater incased within a conductor, and thermally-releasable retaining means under control of the heater, the said conductor being insulated from the body of the heater by a thin layer of insulation. 70

3. A heat-cartridge having a carbonaceous resistance heater incased within a conductor, and thermally-releasable retaining means under control of the heater, the said conductor being slightly separated from the body of the heater between the ends thereof. 75

4. A heat-cartridge having a heating element of carbonaceous resistance material, thermally-releasable retaining means under control of the heating element, a thin layer 85 of insulating material around the heating element, and a non-inflammable casing of conducting material around the said insulating material, the said heating element, insulating material and casing being closely associated with each other.

5. A new construction in an electrical protector, comprising a resistance heater having thermally-releasable retaining means under control thereof, an envelop of conducting material surrounding the heater and separated from the body of same between the ends thereof, a metallic end plate covering the end of the protector and electrically connected with the heater, and insulating 100 material insulating the said end plate from the said envelop of conducting material. 95

6. An electrical protector comprising a thermal core, metallic end terminals therefor at least one of which is secured thereto by heat-susceptible material, a dielectric substance around the said core, a tube of conducting material around the said dielectric substance, insulating material between the ends of the said tube and the said end terminals, and means for connecting the said tube to ground. 110

7. An electrical protector comprising a thermal core, metallic end terminals therefor at least one of which is secured thereto by heat-susceptible material, a dielectric substance around the said core, a tube of conducting material around the said dielectric substance, and means for connecting the said tube to ground. 115

8. An electrical protector comprising a thermal core, metallic end terminals therefor at least one of which is secured thereto by heat-susceptible material, a dielectric substance around the said core, and a tube of conducting material around the said dielectric substance. 120

9. A new construction in an electrical protector, comprising a resistance heater having thermally-releasable retaining means 130

- under control thereof, an envelop of conducting material surrounding the heater and separated from the body of same between the ends thereof, a terminal portion covering the end of the protector and electrically connected with the heater, and insulating material insulating the said terminal portion from the said envelop of conducting material. 5
10. A new construction in a heat-cartridge, comprising a carbonaceous resistance heater incased within a conductor, and thermally-releasable retaining means under control of the heater, the said conductor being separated from the body of the heater along the sides of the latter by a thin layer of insulation interposed between the said heater and conductor and closely associated therewith. 15
11. A new construction in a heat-cartridge, comprising a resistance heater of aggregated comminuted material incased within a conductor, and thermally-releasable retaining means under control of the heater, the said conductor being separated from the body of the heater along the sides of the latter by a thin layer of insulation interposed between the said heater and conductor and closely associated therewith. 20
12. A new construction in a heat-cartridge, comprising a heating element of carbonaceous resistance material, thermally-releasable retaining means under control of the heating element, a thin layer of insulating material around the heating element along the sides of the latter, and a non-inflammable casing of conducting material around the said layer of insulating material, the said heating element, insulating material and casing being closely associated with each other. 25
13. A new construction in a heat-cartridge, comprising a heating element of aggregated comminuted material, thermally-releasable retaining means under control of the heating element, a thin layer of insulating material around the heating element along the sides of the latter, and a non-inflammable casing of conducting material around the said layer of insulating material, the said heating element, insulating material and casing being closely associated with each other. 30
14. A heat-cartridge having a resistance heater of aggregated comminuted material incased within a conductor, and thermally-releasable retaining means under control of the heater, the said conductor being slightly separated from the body of the heater between the ends thereof. 35
15. In an electrical protector having a heater of carbonaceous resistance material with thermally-releasable retaining means under control of the heater and inflammable insulating material around the heater, a 40
- non-inflammable covering of conducting material for the said inflammable insulating material, the said heater, insulating material and covering being closely associated with each other. 45
16. In an electrical protector having a heater of carbonaceous resistance material with thermally-releasable retaining means under control of the heater and non-conducting material around the heater, a non-inflammable covering of conducting material for the said non-conducting material, the said heater, non-conducting material and covering being closely associated with each other. 50
17. In an electrical protector having a heating element of aggregated comminuted material with thermally-releasable retaining means under control of the heating element and inflammable insulating material on the exterior thereof, a covering of non-inflammable conducting material for the said inflammable insulating material and closely associated therewith. 55
18. In an electrical protector having a heating element of aggregated comminuted material with thermally-releasable retaining means under control of the heating element and non-conducting material on the exterior thereof, a covering of non-inflammable conducting material for the said non-conducting material and closely associated therewith. 60
19. In an electrical protector having a heater of carbonaceous resistance material with thermally-releasable retaining means under control of the heater and non-conducting material around the heater, a covering of conducting material for the said non-conducting material, the said heater, non-conducting material and covering being closely associated with each other. 65
20. In an electrical protector having a heating element of aggregated comminuted material with thermally-releasable retaining means under control of the heating element and non-conducting material on the exterior thereof, a covering of conducting material for the said non-conducting material and closely associated therewith. 70
21. A new construction in an electrical protector, comprising a resistance heater having thermally-releasable retaining means under control thereof, an envelop of conducting material surrounding the heater, and separated from the body of same between the ends thereof, and a terminal portion covering an end of the protector and electrically connected with the heater. 75
22. A heat-cartridge comprising a carbonaceous resistance heater contained within a conductor, and thermally-releasable retaining means under control of the heater. 80
23. A heat-cartridge comprising a resistance heater of aggregated comminuted ma- 85

terial contained within a conductor, and thermally-releasable retaining means under control of the heater.

24. A new construction in an electrical protector, comprising a resistance heater having thermally-releasable retaining means under control thereof, an envelop of conducting material surrounding the heater and separated from the body of same between the ends thereof, and a metallic end

plate covering the end of the protector and electrically connected with the heater.

As inventor of the foregoing I hereunto subscribe my name, this 19th day of November, 1913.

PETER K. HIGGINS.
